FUNNEL BRACKET FOR RAYON SPINNING MACHINES

John Joseph Sippel, Upper Darby, Pa., assignor to H. W. Butterworth & Sons Company, Philadelphia, Pa., a corporation of Pennsylvania

Application July 2, 1934, Serial No. 733,519

4 Claims. (Cl. 118—49)

This invention relates to funnel brackets for rayon spinning machines, and more particularly to a funnel bracket especially adapted for use with the modern high speed traverse rayon spinning machine.

In the ordinary rayon spinning machine construction, the funnel bracket comprises a pivoted structure mounted on the traverse mechanism and movable from a substantially vertical inoperative position to a substantially horizontal operative position, the funnel being carried by the outer end of this pivoted structure. The funnel itself is slip-jointed in the outer end of the structure and the weight of the funnel and the weight of the structure itself is depended upon to maintain the structure in its operative position during reciprocation. When, however, the spinning machine is operated at high speeds, there is a tendency of the arm constituting the bracket to swing about its pivot during the reversal of direction of operation and there is, furthermore, a tendency of the funnel to slip in its mounting on the bracket, with the result that an imperfect cake is formed.

Important objects of the present invention are to provide a means for maintaining the arm or bracket in its horizontal operative position which will be so constructed that the arm may be readily moved to its inoperative position without the manipulation of any part other than the bracket itself, and to provide a means which will securely maintain the funnel in its proper position with relation to the arm and will, at the same time, permit ready removal of the funnel, which must be accomplished in order that the bracket may be moved to its inoperative position.

These and other objects I attain by the construction shown in the accompanying drawings wherein, for the purpose of illustration, I have shown a preferred embodiment of my invention and wherein:

Fig. 1 is a sectional view through a portion of the spinning machine embodying a funnel bracket construction in accordance with my invention, the bracket being shown in solid lines in its operative position with the funnel therein, and in dotted lines in its elevated position with the funnel removed;

Fig. 2 is a sectional view through the bracket, taken on line 2—2 of Fig. 3;

Fig. 3 is a plan view of the bracket with the funnel removed;

Fig. 4 is a longitudinal sectional view through the funnel bracket; and

Fig. 5 is an enlarged plan view of the funnel mounting proper.

Referring now more particularly to the drawings, the numeral 10 generally designates a traverse rod of a rayon spinning machine upon which, in accordance with my invention, I mount a support 11 having a recess 12 formed therein which is open at the top and one end of the support. The opposed walls of this recess, adjacent the end opening thereof, flare downwardly and outwardly, as more clearly seen at 13 in Fig. 2. A bracket arm 14 is pivoted within said support, as at 15, and is provided with the usual adjusting screw 16, by means of which the position of the outer end of the arm when in its horizontal operative position may be accurately determined. Since the arm itself and the support 11 are preferably formed of some acid-resistant composition, such as bakelite or hard rubber, a monel metal insert 17 is provided for abutment by the adjusting screw 16.

This screw, in accordance with my invention, provides an anchorage for a spring latch 18, which latch comprises a rubber covered spring having a flat central portion located within a transverse groove 19 formed in the arm. This flat central portion is provided with terminal portions 20 which extend downwardly and converge upon one another, having the outer faces of their tips spaced from one another a distance slightly less than the distance between the upper ends of the flared wall portions 13 so that when the arm is moved downwardly it may enter between the upper ends of these walls, and the rounded corners of the upper ends of the walls indicated at 21 may act to wedge the spring inwardly so that the terminals may pass and enter the recess 11. Having entered the recess 11, these terminals bear against the downwardly flaring wall portions 13 and constantly tend to wedge the arm downwardly so that the adjusting screw 16 is always maintained in proper contact with the abutment 17.

The outer end of the arm has threaded therethrough a sleeve 22 constituting a vertically adjustable support for the funnel 23, this adjustment permitting accurate vertical positioning of the lower or discharge end of the funnel. Mounted in the sleeve is a funnel bushing 24, this bushing having a sliding fit in sleeve 22, and having the funnel secured therein by sulphur, or some similar expedient as is usual. In order to prevent vertical movement between the sleeve and bushing, and at the same time permit the funnel to be rapidly removed, I provide a quick detachable coupling between these elements, such coupling comprising a cam projection 25 upon the head of bushing 24 co-acting with an undercut

and similar cam surface 26 formed upon the head of sleeve 22. The bushing is provided with wing projections 27 upon its head so that it may be readily rotated to engage or disengage the coupling. The head of sleeve 22 is formed as a nut so that this sleeve may be readily rotated and a lock nut 28 is provided for securing this sleeve in its adjusted positions.

Since the construction is capable of considerable modification without in any manner departing from the spirit of the invention, I do not wish to be understood as limiting myself thereto except as hereinafter claimed.

I claim:

15 1. In rayon spinning apparatus, a reciprocable support, a funnel bracket pivoted thereto for movement from a substantially vertical inoperative position to a substantially horizontal operative position, a spring latch maintaining said bracket in its operative position and releasable by application of upward pressure on the bracket, and a funnel carried by the bracket.

20 2. In rayon spinning apparatus, a reciprocable support, a funnel bracket pivoted thereto for movement from a substantially vertical inoperative position to a substantially horizontal operative position, a spring latch maintaining said bracket in its operative position and releasable by

application of upward pressure on the bracket, and a funnel carried by the bracket, said support embodying confronting downwardly divergent walls, said spring latch having wedging engagement against said walls in the operative position of the bracket.

3. In rayon spinning apparatus, a reciprocable support, a funnel bracket pivoted thereto for movement from a substantially vertical inoperative position to a substantially horizontal operative position, a spring latch maintaining said bracket in its operative position and releasable by application of upward pressure on the bracket, a funnel carried by the bracket, and means detachably connecting the funnel and bracket constructed and arranged to prevent movement of the funnel in the bracket.

4. In rayon spinning apparatus, a reciprocable support, a funnel bracket pivoted thereto for movement from a substantially vertical inoperative position to a substantially horizontal operative position, a spring latch maintaining said bracket in its operative position and releasable by application of upward pressure on the bracket, a funnel carried by the bracket, and a quick detachable positive connection between the funnel and bracket.

JOHN JOSEPH SIPPEL.
